SKIMMING BOARD

Daniel B. Looney III, 23271 Road 10, and Frank P. Gordon, 11771 Ave. 21, both of Chowchilla, Calif. 96610

Filed Jan. 9, 1967, Ser. No. 5,350

Term of patent 14 years

(Cl. D71—1)

FIG. 1.

FIG. 2.

FIG. 3.

FIG. 4.

FIG. 5.

FIG. 6.

FIG. 1 is a top plan view of a skimming board showing our new design.

FIG. 2 is a side elevation thereof with the opposite side being identical to the side shown.

FIG. 3 is a bottom plan view thereof.

FIG. 4 is an end elevation thereof with the opposite end being identical to the end shown.

FIG. 5 is a transverse vertical section therethrough taken on line 5—5 of FIG. 1.

FIG. 6 is a perspective thereof.

We claim:

The ornamental design for a skimming board, as shown and described.
